Application May 2, 1942, Serial No. 441,540

14 Claims. (Cl. 12—60)

This invention pertains to the art of fitting shoes to feet, and more particularly to lifts which may be formed to appropriate shape to accomplish such fitting and to holders for such lifts adapted to support them in proper position with reference to forming apparatus. This application is a continuation in part of application Serial No. 344,458, filed July 8, 1940.

The above-mentioned application describes apparatus whereby a lift-blank may be formed accurately to a shape such that its thickness at any point is equal to the difference between the height of the sole of the foot and the height of the inside sole surface of the shoe. Such apparatus provides a forming tool which is suitably driven and controlled so as to operate upon the lift-blank by cutting or otherwise forming the same at different points of its surface so as to reduce it to the desired configuration.

One of the objects of this invention is to provide a lift-blank suitable for use in such apparatus.

Another object is to provide a holder properly fitted to the apparatus and arranged to hold the lift-blank in proper relation thereto.

Another object is to provide such a holder and blank in combination so arranged that the blank must be positioned upon the holder in a proper manner so that it will be correctly oriented with respect to the forming apparatus.

Another object is to provide such a lift-blank holder combination so arranged that different shaped blanks for right and left shoes, respectively, may be placed in the same holder, and in each case engaged with securing devices so arranged that the blank cannot be properly secured except in proper orientation and alignment.

Another object is to provide a blank so formed as to require the least possible amount of reforming in the aforesaid apparatus in order to 40 remake it fit a particular wearer. Another object is to provide novel anchoring means on the blank and on the holder to correspond with each other so that any blank may be quickly and accurately mounted in the holder.

Further objects will appear from the following description taken in connection with the accompanying drawings, in which:

Figure 1 is a plan view of the lift-blank table of the forming machine, such as described in the above-mentioned application;

Figure 2 is a section taken on line 2—2 of Figure 1;

Figure 3 is a section on line 3—3 of Figure 2;

Figure 4 is a plan view of the blank holder shown in Figures 1 and 2;

Figure 5 is a top view in perspective of one form of lift-blank;

Figure 6 is a plan view slightly enlarged of another form of blank holder with another form of blank in place thereon;

Figure 7 is a bottom view of the holder shown in Figure 6;

Figure 8 is a section on line 8—8 of Figure 6;

Figure 9 is a perspective view of a lift-blank of the type shown in Figure 6.

In the apparatus described in the above-mentioned application, mechanism is provided for taking a model of the sole surface of a foot and placing such model in a suitable seat in the apparatus. A support is also provided in the apparatus for receiving the shoe which is to be fitted

20 to the foot modeled, and for supporting it in proper position. At another location on the machine a table is provided to hold the lift blank. The apparatus is then arranged with control means, including a feeler which may be made to

25 follow the surface of the foot model and a stylus which may at the same time be made to follow the inside sole surface of the shoe. These devices cooperate through suitable control mechanism to control the movements of the lift-blank table and the forming tool, so as to move them relatively to each other in such a manner that the lift is formed by the tool to a thickness at every point thereof equal to the difference in the heights of the model and the shoe surface at the 30 corresponding points.

Such a lift-blank table is shown at 54 in Figure 1. In this application the same reference numerals are used as in the parent application. The table 54 is supported by a pair of arms 55 which are hinged at their other ends to the apparatus, these connections not being shown in the drawings. Table 54 is equipped with a longitudinal bar 73, placed below the table and engaged by a pair of rollers 74 on an arm 73, attached to and movable by the aforesaid apparatus.

These connections also are not shown in the drawings as they are part of the forming apparatus. However, the operation of said apparatus is such that the arm 73, carrying the roller 74, is operated so as to raise and lower the table 54 in accordance with the height of the inside sole surface of the shoe. At the same time a forming tool, such as a cutter 68, is operated by the apparatus to rise and fall in accordance with 45 the height of the model of the foot sole. These

connections are not shown in the present drawings, being part of the forming apparatus. The lift blank, therefore, is operated upon by these combined movements, and as the feeler and the stylus of the forming machine are moved over the respective surfaces of the model and the shoe sole, the table 54 is raised and lowered, while the tool 68 moves over the surface of the blank and forms it to the corresponding shape.

One arrangement for mounting the lift-blank in the holder 54 is shown in Figures 1 to 4, inclusive. The table 54 comprises generally the form of a shallow pan provided on the inside thereof with side rails 131 adapted to receive and locate the blank-supporting plate or holder 57. This plate may be removably fitted into the pan 54. For this purpose the plate may be provided at one end with a perforation 133 engageable by a retaining spring 134 within the pan 54. The front end of the plate is turned upwardly and provided with a vertical flange 135, fitting into an opening in the front wall of the pan 54. Mounted on the flange 135 is a handle 136, the side extending flange portions being adapted to engage the front ends of the rails 131. This secures the plate against the tension of the spring 134.

The plate is provided at its front end with a pair of perforations 139, having a sort of key-hole shape adapted to receive a downwardly extending key 140 on a holding bar 141, which is engaged under a facing 146 on the top side of the lift-blank 142 with the key 140 projecting downwardly through an opening in the facing. A similar key 143, similarly mounted on the opposite end of the lift blank, is passed through the perforation 133 and engaged by a spring tension bar 144, as shown in Figure 2, so as to secure the lift-blank in place in the holder, and, at the same time, tension the same lengthwise so as to keep it flat.

The lift-blank may be formed as illustrated in Figures 1 and 5. Figure 1 shows a plan view of what is the upper surface of the blank while being operated upon, but which, according to the method of this invention, becomes the under-surface when the lift is applied to the shoe. Figure 5 shows the opposite surface to that of Figure 1. Figure 5 shows that this surface is substantially flat, while the surface operated upon, as shown in Figure 1, may have an elevated portion 145 located at that part of the blank which must usually be formed higher.

As shown in Figure 5, the flat side of the blank may be provided with a suitable finished surface, such as the facing or sock lining 146 of fabric, leather, or the like, so that when the opposite face of the blank has been formed and the same is inverted and placed in a shoe, this surface will be uppermost and will provide a finished surface for the inside of the shoe. In addition to the sock lining 146, a chart 147 may be applied to the blank in any suitable manner. This chart has provided on a diagram the outlines to which the lift is to be trimmed for several different sizes of shoes. As shown at 149, the lengths of the different shoe sizes are given so as to indicate to the operator the point at which the lift is to terminate for the respective sizes. At 150 are given designations of sizes, and along the outside of the foot is a series of outlines 150 to which the lift may be trimmed. Accordingly, this chart serves as a guide to the operator by means of which he may quickly

trim the finished lift to the proper shoe to be fitted. As this is usually done after the lift has been formed, the thickness of the lift along the outline to be trimmed is usually very small and the trimming operation is therefore easily and quickly performed with the aid of these lines. The chart 147 may be removably attached to the blank, as, for instance, by securing it adhesively at one or both ends, preferably beyond the limits of the diagram so that the secured portions are eventually trimmed off. This diagram may also be placed directly on the sock lining, in which case it will usually remain on the lift after it is finished.

The table or pan 54 is so positioned that the forming tool 68 will operate within the side flanges thereof, and in order to prevent the cuttings from being scattered about one or more closure plates 117 may be placed upon the top edges of said flanges. In the arrangement illustrated in Figures 2 and 3 a series of such plates is employed, each having a perforation through which the forming tool may be inserted, but the perforations in the successive sheets being of different sizes. The lower sheet has a large perforation which permits the forming tool to move over the greater portion of the area of the blank without requiring shifting of the plate except when the tool moves to the extreme limits of that area. The succeeding plate, resting upon the first plate, is large enough to cover the perforation in the first plate and is itself provided with a smaller perforation such that the tool may move about therewithout without shifting the second plate except when near the edges, and then the shift will not be sufficient to uncover the perforation in the lower plate. Thus, each succeeding plate has a smaller opening and covers the opening in the one below it. By this arrangement the forming tool may be moved over the entire area of the blank and still the pan 54 will remain covered so that the cuttings are not thrown about.

In order to carry away the cuttings, the lower portion of the pan 54 may be formed to a spout 118, connected in any suitable manner to suction apparatus, not shown.

It will be noted that in the blank shown in Figure 5 the key portions of the holder bars 141 and 143 are displaced laterally with respect to each other. The perforations 139 in the holder 57 are also displaced laterally with respect to the opening 133. The openings 139 are displaced in opposite directions from the axis of the holder passing through the center of the opening 133, so that one of them may be engaged by the holder of a right-hand blank and the other for the holder of a left-hand blank. It also will be noted, from the shape of the blank as shown in Figure 1 and its position when mounted in the holder, that it is impossible to put a right blank into the left socket 139, or vice versa. Also, when the blank is thus properly mounted in the openings 133 and 139, it is accurately aligned on the holder and tensioned to hold it flat.

Figures 6 to 9, inclusive, illustrate another blank and holder combination embodying this invention. In the lift blank shown in these figures the facing or sock lining 146 is also extended beyond the ends of the blank a substantial distance to provide for securing it to the anchoring devices which anchor it to the holder and for clearance for the cutter 68. These extensions are indicated at 155 in Figure 9. In this case, however, instead of being secured to a holder bar,

such as 141 and 143, these extensions are secured directly to the holder 157. In the embodiment shown, the holder is provided with a series of anchoring members in the form of hooks 156. These may be formed by punching tongues from the top plate of the holder, but severing them only partly and bending them upwardly, as shown in Figure 8. With this arrangement the extensions 155 of the facing may be provided with perforations 158 spaced so as to match the hooks 156, so that the hooks may be inserted, as shown in Figures 6 and 8, so as to secure the facing to the top of the holder. The hooks are arranged in a row across the holder. However, their spacing is non-uniform. Certain of the hooks are spaced at uniform intervals, as indicated at *a*. However, at at least one point near each side edge of the holder the distance between successive hooks is changed, as indicated at *b*. The distance *b* may be either greater or less than the distance *a*. It is selected so that it is not an even multiple of the distance *a*, but preferably has no particular arithmetical relation to the distance *a*. The purpose of this arrangement is to provide a break in the regular spacing of the hooks. The spacing of the perforations 158 in the facing of the blank corresponds exactly to that of the hooks on the holder. However, since each blank is either a right or a left, it will have perforations matching only a certain number of the hooks at one side of the holder 157. However, it must, of course, have the same regularity of spacing for the perforations 158 as is used for the hooks 156 so that the perforations may be properly engaged with the hooks, as already explained. The provision of the odd spacing *b* makes it impossible to shift the blank to one side or the other and still engage it with the hooks, as in that case some of the holes will not match. It will be seen, therefore, that this arrangement insures the accurate alignment of the blank on the holder.

In order to secure the other end of the blank and tension the same, a sliding frame 159 is mounted in rails 160 on the underneath side of the holder, as shown in Figure 7. This frame may slide in the rails 160 endwise of the holder, and has secured thereto a manipulating bar 161. A compression spring 162 surrounds the bar 161 so as to bear at one end against the frame 159 and at the other against a stop bracket 163 secured to the holder. This provides that the frame 159 is forced outwardly or to the right of Figure 7 by the spring 162. The bar 161 may be provided with a handle portion 164, by means of which it may be retracted, and the bracket 163 may be provided with a hook 165, behind which the handle 164 may be lodged after retracting the spring, so as to hold the frame 159 in retracted position.

The frame 159 is provided with a series of windows 166, spaced so as to match a series of slots 167 in the top plate of the holder 57, the arrangement being such that each one of these windows slides back and forth beneath one of the slots 167. One edge of each of the windows 166 is provided with a series of teeth 168, and the corresponding extension 155 of the lift-blank is provided with a series of perforations 169 matching the teeth 168. The arrangement is such that the extension 155 may be passed through an appropriate pair of slots 167 until the perforations 169 pass below the top plate of the holder in a position to be engaged by the teeth 168. When the teeth have been thus engaged in the perfora-

tions, the handle 164 may be released from the hook 165 and the spring 162 will then force the frame 159 to the right (Figure 7), thereby placing the facing of the lift-blank in tension between the teeth 168 and the hooks 156. This locates the blank on the holder, as shown in Figure 6, in proper position to be operated upon by the tool 68. It will be noted that here also the slots 167 and the windows 166 do not extend continuously across the holder, but are interrupted by bars 171 and 170, respectively. The extension 155 of the lift-blank facing is provided with a notch 172 to receive the bars 170 and 171. It will be noted that each lift-blank is provided with a notch 172 at only one side thereof, and similarly the odd spacing *b* of the perforations 158 is provided at only one side of the blank. This distinguishes between right and left blanks, so that a right-blank cannot be positioned on that side of the holder intended for a left blank, or vice versa. It will be noted also that by cooperation of the odd spacings, provided by the notch 172 and the odd distance *b*, there is no way to place the blank on the holder except in such position as to be accurately aligned for operation of the forming tool.

The lift-blank itself is formed so as to require a minimum of cutting in order to shape it to the proper shape in the forming machine. The facing 155, as already described, may be formed of leather, fabric, or other suitable tensionable material so that it can be stretched taut in the holder. The body portion of the lift-blank may be made of any suitable material which can be formed by the forming tool 68. A satisfactory material has been found to be cork. Cork made up in sheet form out of granular cork, consolidated by pressure with or without a suitable binder, has been found very satisfactory. It has also been found that the form of blank shown in Figures 6 and 9 requires a minimum of cutting. In this form what may be termed the top surface 173 in Figure 9 is usually flat, that is, substantially parallel with the facing 55, and of a suitable thickness, usually not more than $\frac{1}{2}$ inch. The ends are beveled downwardly, as indicated at 174 and 175. The left-hand side portion, indicated at 176 in Figure 9, is beveled downwardly and is given a form roughly approximating the outside curve of a foot. The inner or right-hand surface of Figure 9, indicated at 177, is also beveled, but in a particular manner. This surface follows fairly accurately the shape of the inside surface of a shoe at the arch of the foot. The line 178 is given the form in horizontal projection of the line of the inner longitudinal arch of the average foot. Since the lift-blanks are made up in different sizes, there being one size of blank for each shoe-size, the form of this line can be closely approximated to fit the average foot. The angle of bevel of the surface 177 is also made to fit the bevel of the corresponding portion of the shoe, namely, that portion of the upper which engages under the inner longitudinal arch. This angle of bevel is not constant, but varies from point to point along the curve 178, so that the surface 177 forms a warped or twisted surface, such a surface, for instance, as may be generated by the movement of a straight line which intersects the curve 178 and moves therealong but continually changes its angle with respect to the plane of the facing 155. Such a surface will have straight line elements, but will be warped or twisted from one end to the other. Finally, a fifth beveled surface is formed around

the outer edge of the blank so as to form it roughly to the shape of a shoe. This surface is indicated at 179 and may be considered as starting about at the point *c* in Figure 9, which is the terminus of the surface 177, and extending all the way around the heel portion of the blank and up the left side to the forward limit of the blank.

This form of blank not only reduces the necessary cutting to a minimum when the blank is fitted to a foot, but the arrangement is such that the surface 177 ordinarily is not altered by the forming tool 63. One reason for preforming this surface 177 as nearly as possible to its final form is that the portion of the shoe which is engaged by this portion of the blank is a part of the upper, which is of soft leather and relatively flexible. Accordingly, this part of the shoe does not present a solid abutment which may be easily followed by the stylus of the forming machine. Accordingly, by preforming this part of the blank to its final form and then forming the remaining surface of the lift to conform to this preformed surface, an accurately fitted lift may be made which will fit the shoe at all points.

It will be seen that this invention provides a blank-and-holder combination whereby a lift-blank may be accurately positioned and securely supported in position for operation thereon of forming apparatus of the character described. The blank, although constructed mainly of bulk material, is provided with a facing of tensionable material, and is mounted in the holder by securing the facing and tensioning the same in the holder. The anchoring means engaging the facing is so organized with respect to the cooperating means on the blank that the mounting can be carried out in only one way, such as to position the blank correctly in the machine. By arranging the anchoring devices in perverted or pervertible relation, right and left blanks may be handled on the same devices and each will be properly positioned.

While the invention has been described in each case as embodied in a unitary device or assembly, it will be understood that individual features or subcombinations may be employed by themselves or in other combinations, and that such use is contemplated by this invention when within the scope of the appended claims. It will be understood, also, that various changes may be made in the details of construction within the scope of the appended claims without departing from the spirit of this invention, and that the invention is not limited to the specific details shown and described.

The invention having thus been described, what is claimed is:

1. A lift-blank of the character described, comprising, a substantially flat body of cork having a substantially plane layer of tensile-strong fabric incorporated therewith, and attaching means associated with the blank engageable with tensioning means and constructed and arranged for tensioning the blank in a holder.

2. A lift-blank of the character described, comprising, a substantially flat body of relatively soft lift-pad material workable by a forming tool, a substantially plane layer of tensile-strong fabric incorporated therewith, and attaching means associated with the blank engageable with tensioning means and constructed and arranged for tensioning the blank in a holder.

3. A lift-blank provided on one surface thereof with a sock lining, and with a chart remov-

ably mounted over said sock lining in predetermined orientation with respect to the blank and provided with one or more sole outlines providing a guide for trimming a lift to a predetermined sole size.

5 4. A lift-blank of the character described, comprising, a body of formable material, and a facing of tensionable sheet material attached to said body, said facing having anchorage-engaging means at the ends thereof.

10 5. A lift-blank of the character described, comprising, a body of formable material, and a facing of tensionable sheet material attached to said body, said facing having anchorage-engaging means at the ends thereof formed to a pervertible pattern in order to distinguish right from left blanks.

15 6. A lift-blank of the character described, comprising, a body of formable material, and a facing of tensionable sheet material attached to said body, said facing having anchorage-engaging perforations at the ends thereof.

20 7. A lift-blank of the character described, comprising, a body of formable material, and a facing of tensionable sheet material attached to said body, said facing having anchorage-engaging perforations at the ends thereof arranged in a pervertible pattern in order to distinguish right from left blanks.

25 8. A lift-blank of the character described, comprising, a body of formable material, and a facing of tensionable sheet material attached to said body, said facing having a series of anchorage-engaging perforations uniformly spaced except for a break in the spacing located laterally of the axis of the blank.

30 9. A lift-blank of the character described, comprising, a body of formable material, and a facing of tensionable sheet material attached to said body, said facing having anchorage-engaging perforations arranged with nonuniform spacing in a pervertible pattern.

35 10. A lift-blank of the character described, comprising, a body of formable material, and a facing of tensionable sheet material attached to said body and extending a substantial distance beyond the ends thereof.

40 11. A lift-blank holder of the character described, comprising, a supporting plate mountable in a forming machine, a series of anchorage hooks at one end of said plate engageable in perforations in a blank to anchor the same, and tensioning means at the other end of said plate attachable to the blank and operable to tension the same.

45 12. A lift-blank holder of the character described, comprising, a supporting plate mountable in a forming machine, blank-anchorage means at one end of said plate, an anchoring member movably mounted at the other end of said plate and having teeth engageable in perforations in the blank to secure the same, and spring means for moving said member to tension the blank.

55 13. A lift-blank holder of the character described, comprising, a supporting plate mountable in a forming machine, blank-anchorage means at one end of said plate, an anchoring member movably mounted at the other end of said plate and having teeth engageable in perforations in the blank to secure the same, and spring means for moving said member to tension the blank, said teeth being non-uniformly spaced in a pattern symmetrical with respect to the axis of the plate but so arranged on either side of said axis as to match either of a pair of mutually per-

verted patterns of perforations in a pair of right and left blanks.

14. A lift-blank holder of the character described, comprising, a supporting plate mountable in a forming machine, blank-anchorage means at one end of said plate, an anchoring member movably mounted at the other end of said plate and having teeth engageable in perforations in the blank to secure the same, and spring means for moving said member to tension the blank, said teeth being non-uniformly spaced

5 in a pattern symmetrical with respect to the axis of the plate but so arranged on either side of said axis that a certain number of said teeth counted from one edge of said plate will form a pattern which is perverted with respect to that formed by the same number of teeth counted from the opposite edge of said plate.
